(57) **CLAIM**

The ornamental design for a radio unit for mobile phone, as shown and described.

DESCRIPTION

FIG. 1 is a front, top perspective view of a radio unit for mobile phone showing my new design;

FIG. 2 is a rear, top perspective view thereof;

FIG. 3 is a front elevational view thereof;

FIG. 4 is a top plan view thereof;

FIG. 5 is a rear elevational view thereof;

FIG. 6 is a bottom plan perspective view thereof;

FIG. 7 is a left side elevational view thereof; and,

FIG. 8 is a right side elevational view thereof.

The broken line showing of a cord on the radio unit for mobile phone is for illustrative purposes only and forms no part of the claimed design.
